RAILWAY DRAFT RIGGING

Stacy B. Haseltine, Chicago, Ill., assignor to W. H. Miner, Inc., Chicago, Ill., a corporation of Delaware

Application February 15, 1929. Serial No. 340,153

5 Claims. (Cl. 213—22)

This invention relates to improvements in railway draft riggings.

The main object of the invention is to provide a railway draft rigging including the usual standard coupler and cooperating shock absorbing means connected to the coupler by a yoke having a keyed connection with the coupler, wherein the coupler has greater travel in buff than in draft to compress the shock absorbing means to a greater extent, thereby providing higher resistance to buffing than draft shocks, and in connection with which a main outer follower cooperating with outer stop lugs on the usual center sills is employed and outward movement of the coupler in draft is limited by engagement of the coupler key with stop means on the sills, the coupler key being guided in slots provided in the sills and outer stop lugs, the follower having an extension engaging the inner end of the coupler shank, whereby the follower is disposed inwardly of the inner ends of the slots of the sills and the outer stop plugs, thus permitting the use of stop lugs having solid walls at the inner ends of the slots, thereby greatly increasing the strength of the stop shoulder portions thereof.

A further object of the invention is to provide a railway draft rigging of the character specified in the preceding paragraph, wherein the main follower is also provided with a rear extension whereby the follower is materially strengthened and is adapted to properly cooperate with the wedge of the friction shock absorbing mechanism and with the coupler means having longer travel in buff than in draft.

A further object of the invention is to provide an outer follower for a railway draft rigging having forward and rear extensions adapted to cooperate respectively with the inner end of the coupler shank and the outer end of the wedge of the friction shock absorbing mechanism, the forward extension being of such a width as to freely pass between the side walls of a hooded yoke and the rearward extension being laterally enlarged to reinforce the main follower, the over-all width of said enlarged portion of the rear extension exceeding the spacing between the side walls of the hood, whereby it is impossible to assemble the follower incorrectly with the other parts of the draft rigging, that is, in a position with the extensions reversed.

Other and further objects of the invention will more clearly appear from the description and claims hereinafter following.

55 In the drawing forming a part of this specifi-

cation, Figure 1 is a vertical longitudinal sectional view of the underframe structure at one end of the car, illustrating my improvements in connection therewith. Figure 2 is a horizontal longitudinal sectional view, corresponding substantially to the line 2—2 of Figure 1. And Figure 3 is a vertical transverse sectional view, corresponding substantially to the line 3—3 of Figure 1.

In said drawing, 10—10 indicates the usual channel-shaped center or draft sills of a railway car underframe, said sills being spaced the standard distance apart and provided with rear stop lugs 11—11 forming a part of the usual bolster filer casting of the underframe structure, the stop lugs 11 proper being formed on forwardly extending arms of said casting. A standard coupler is indicated at 12, the same being provided with the usual head 13, which is only partly shown in the drawing.

In carrying out my invention, I provide the sills 10 with aligned coupler key guide slots 14—14 at the forward ends thereof. The casting 15, forming a combined striking member and front stop lugs, is secured to the front ends of the center sills 10. This casting comprises a pair of rearwardly extending side arms 16—16 which form the front stop lugs of the railway draft rigging and by which the casting is fixed to the draft sills. The stop lug members 16 are provided with aligned slots 17—17 which register with the slots 14 of the sills.

At the forward end, the casting 15 is provided with laterally extending flange portions 117—117 and a transversely disposed top section 18 forming the striking plate proper. The striking plate member is reinforced by top and bottom horizontal walls 19 and 20, the wall 19 having a vertical flange portion 21 which is secured to the end sill structure 22 of the car. The opening defined by the side portions 117 and the top member 18 of the casting accommodates the coupler shank. At the forward ends, the walls of the guide slots 17 are reinforced by outwardly projecting lateral vertical flanges 23—23 braced by horizontal webs formed integral with the flanges 117. The front end walls of the slots 17, together with the reinforcing flanges 23, form outer stop members cooperating with the coupler key to limit the outward movement thereof. The slots 17 terminate short of the inner ends of the lug members 16, whereby solid wall portions are provided at the inner ends of said slots, thus reinforcing the stop shoulder portions of said lugs.

A friction shock absorbing mechanism of

standard width and height is disposed between the draft sills, the same including the usual friction shell 24, friction shoes 25, wedge block 26 and main spring resistance 27. The friction shock absorbing mechanism needs no further description as the same is old and well known in the art. The inner end of the friction shell 24 cooperates with the rear stop lugs 11 in the usual manner.

10 A follower 28 is interposed between the inner end of the shank of the coupler 12 and the wedge member of the friction shock absorbing mechanism. The follower 28 is in the form of a relatively heavy substantially rectangular plate having a centrally disposed lug or extension 29 on the front side thereof, engaging directly the inner end of the coupler shank.

On the rear side, the follower 28 is provided with another boss or extension 30 which bears 20 on the front end of the wedge block 26. The extension 30 is somewhat longer than the extension 29 and is provided with lateral enlargements in the form of lengthwise extending ribs or webs 130 at the opposite sides thereof, as clearly 25 shown in Figures 2 and 3. The over-all width of the extension 30 at said enlargements is considerably greater than the space between the side walls at the inner end of the hood of the yoke, whereby the follower cannot be incorrectly 30 assembled with the yoke, that is, in a reverse position from that shown in the drawing, inasmuch as the extension 30 cannot be entered between the side walls of the hood of the yoke, thus assuring the proper positioning of the main follower 35 with the longer extension disposed rearwardly. It will be appreciated that it is highly important that no error be made in assembling the parts of the mechanism, as a reversal of the follower would not only materially affect the 40 length of the compression stroke of the gear in buff, but would cause an undesirable separation of the follower and wedge block in full release position of the parts. In addition, the ribs 130 serve to strengthen both the extension 30 and 45 the follower plate itself, reinforcing the latter against bending between the opposite side ends. Outward movement of the follower 28 is limited by engagement with the shoulders of the stop lug members 16.

50 The friction shock absorbing mechanism and the front follower 28 are disposed within a yoke 31 having top and bottom arms, a vertical connecting portion at the rear end thereof and a hooded front end portion 32. The hood portion 55 32 is defined by top and bottom walls forming extensions of the arms of the yoke and spaced connecting side walls 33-33. The side walls are slotted, as indicated at 34-34, to accommodate the coupler key 35 which connects the yoke to 60 the coupler shank. The key 35 extends through an opening in the coupler shank, the slots 34 of the yoke, and has the outer ends thereof working in the slots of the front stop lugs and draft sills. The key is preferably of the headed type 65 and is secured by the usual cotter pin or other holding device. The side walls of the hood are spaced from the side edges of the shank of the coupler so as to permit the necessary swinging movement of the latter. The top wall of the 70 hood is cut away, as indicated at 36, at the forward end of the yoke, so as to provide the necessary clearance between the same and the horizontal web 20 of the combined striking casting and front stop lug member during outward 75 movement of the coupler and yoke. The bot-

tom wall of the hood of the yoke has the forward end portion thereof upwardly offset, as indicated at 37, to provide a supporting ledge for the coupler shank closely adjacent the head of the same. The yoke is supported by plates 40-40 secured 80 to the bottom flanges of the sills 10-10.

The slots in the front stop lugs and center sills are of such a length that movement of the key 35, the coupler and the yoke will be limited 85 before the friction shell 24 engages the follower 28. The slots of the stop lugs and sills extend inwardly such a distance so as to permit compression of the friction shock absorbing mechanism to an extent where the front follower 28 will engage the friction shell, without the key coming 90 in contact with the inner end walls of said slots. From the foregoing, it will be evident that the compression of the friction shock absorbing mechanism is greater during the inward or buffering movement of the coupler than upon outward or draft movement thereof. The travel of the coupler inwardly during buff is preferably approximately twice the travel of the same during draft.

95 In the normal position of the parts, the front follower is in engagement with the stop shoulders of the stop lug members 16 and has the enlargements or projections at the front and rear sides thereof bearing respectively on the inner end of the coupler shank and the front end of the wedge block, the coupler key 35 being in engagement with the front end walls of the slots of the hood of the yoke and spaced from the rear end walls of said slots. In this position of the parts, the inner end walls of the slots 34 of the hood are 100 spaced forwardly of the inner end walls of the slots in the stop lugs and sills, but the length of the slots 34 is such that full compression of the gear in draft is possible without bringing the keys 35 into engagement with the inner ends of 115 the slots.

105 The operation of my improved railway draft rigging, assuming a pulling or draft action as applied to the coupler, is as follows:

110 The yoke will be pulled forwardly by means 120 of the coupler key, thereby compressing the friction shock absorbing means between the inner end of the yoke and the follower 28 which is held stationary by the stop lugs 16. The outward movement of the coupler is finally limited by 125 engagement of the front edge of the key 35 with the front end walls of the slots of the stop lugs, whereupon movement of the yoke and compression of the friction shock absorbing mechanism will also be limited. The draft movement of the 130 coupler is thus equal to the spacing between the key and the front end walls of the guide slots of the stop lugs. The expansive action of the friction shock absorbing mechanism after a draft action will force the friction shell rearwardly 135 until arrested by the stop lugs 11 carrying the yoke therewith and restoring all of the parts to the normal position shown in the drawing. During the buffering action, the coupler will be forced inwardly, carrying the follower 28 therewith and 140 compressing the friction shock absorbing mechanism between the follower and the stop lugs 11. Inasmuch as the follower 28 is provided with the projection 30, movement of the follower continues until the same is limited by engagement with 145 the front end of the friction shell, the projection 30 being of such a size as to enter the front end of the shell and force the wedge block inwardly beyond the front end of the same. The amount of travel of the coupler in buff is there- 150

fore equal to the spacing between the follower 28 and the front end of the friction shell, which is substantially double the spacing between the key and the front stop walls of the key slots 5 of the front stop lugs, but during a buffing action no rearward movement of the yoke occurs, due to the length of the slots 34 thereof.

Expansive action of the friction shock absorbing mechanism, when the actuating force is reduced, will return the follower 28 and the coupler to the normal full release position shown in the drawing, outward movement of the follower being limited by the stop lugs 16, as hereinbefore pointed out.

15 From the preceding description, taken in connection with the drawing, it will be evident that I have provided a railway draft rigging having relatively longer travel in buff than in draft, of simple construction, wherein the shank of 20 the coupler is adequately supported to maintain the horizontal position thereof and wherein a coupler of standard size and a friction shock absorbing mechanism of standard width and height may be employed. The use of the coupler 25 of standard size is made possible by the employment of the main follower having the extension at the front sides thereof cooperating with the inner end of the coupler shank.

It is further pointed out that by providing the 30 extension on the forward side of the front follower, the main portion of the follower is spaced inwardly of the key receiving slots of the stop lugs, thereby permitting the use of stop lugs having solid wall portions at the inner ends of the 35 key guide slots, whereby the stop shoulder portions of the lugs are of solid metal and of maximum strength. This arrangement also provides for a yoke having a hood of rugged design, inasmuch as the slots in the side walls of the yoke 40 hood are closed at the rear ends, thereby providing sufficient metal rearwardly of the slots.

While I have herein shown and described what I consider the preferred manner of carrying out 45 my invention, the same is merely illustrative and I contemplate all changes and modifications which come within the scope of the claims appended hereto.

I claim:

1. In a railway draft rigging, the combination 50 with center sills; of a coupler having longer travel in buff than in draft; a friction shock absorbing mechanism including a friction shell, friction shoes and cooperating wedge member, said wedge member and shell having relative movement toward and away from each other; a yoke within 55 which said friction shock absorbing mechanism is disposed; a key connecting the yoke to the coupler; inner and outer stop lugs on the sills, said outer lugs and sills having aligned slots within 60 in which the outer ends of the key work, the slots of the outer lugs being closed at the outer and inner ends by solid walls, the outer end walls of said slots forming outer stop means for the key; and a main follower interposed between the 65 inner end of the coupler and friction shock absorbing mechanism, said follower having its outward movement limited by engagement with the stop lugs, said follower having extensions at the front and rear sides thereof engaging the inner 70 end of the coupler and the wedge of the friction shock absorbing mechanism respectively in the full release position of the parts.

2. In a railway draft rigging, the combination 75 with center sills having front and rear stop lugs; of a friction shock absorbing mechanism disposed

between said sills, said friction shock absorbing mechanism including a relatively movable friction shell and wedge block, said shell cooperating with the rear stop lugs; a coupler; a main follower interposed between the coupler and wedge of the friction shock absorbing mechanism and cooperating with the outer stop lugs, said follower having front and rear extensions engaging the inner end of the coupler shank and the wedge of the friction shock absorbing mechanism, respectively; a yoke within which said friction shock absorbing mechanism and follower are disposed; and a key connecting the coupler and yoke, said key working in slots in the draft sills and having its outward movement limited by engagement with the outer end walls of said slots, thereby limiting the compression stroke of the shock absorbing mechanism in draft.

3. In a railway draft rigging, the combination with center sills having front and rear stop lugs; of a friction shock absorbing mechanism between said sills, said mechanism including a relatively movable friction shell and wedge block; a yoke within which said mechanism is disposed, said yoke having a hood member provided with spaced side walls; a coupler having the shank thereof extending into said hood between the side walls; a main follower interposed between the inner end of the coupler shank and wedge and cooperating with the front stop lugs, said follower having a forward extension working freely between the side walls of the hood and engaging the inner end of the coupler shank and a rearward extension engaging the wedge block, said rearward extension being laterally enlarged to reinforce said follower, said extension being of over-all width at said enlarged portion exceeding the spacing between the side walls of the hood.

4. In a railway draft rigging, the combination with a friction shock absorbing mechanism including a friction shell and cooperating friction elements; of a coupler having a shank; a hooded yoke connected to the coupler, the hood of said yoke having spaced side walls adapted to freely accommodate the coupler shank therebetween; and a main follower having flat front and rear faces provided with central projections adapted to cooperate respectively with the friction shock absorbing mechanism and the inner end of the coupler shank, the flat face at the rear of said follower being engageable with the friction shell, said projection on the front of the follower corresponding in cross-sectional size to the coupler shank and said projection on the rear of the follower being of greater width than the spacing between the side walls of the hood of the yoke and of such an overall size as to telescope freely within the friction shell.

5. In a railway draft rigging, the combination with spaced draft sills; of front stop means presenting stop shoulders, said means being secured to the sills, said stop means and sills having aligned coupler key slots spaced forwardly from said stop shoulders; a hooded yoke; a shock absorbing means and cooperating front follower within the yoke, said shock absorbing means including a friction shell, outward movement of said front follower in full release position of the railway draft rigging being limited by said stop shoulders; a coupler having a shank extending into said yoke; a key operatively connecting the coupler to the yoke, said key extending into and being movable within the slots of the stop means and sills; an abutment means on the forward side of said follower fixed with respect to and

projecting beyond said stop means in full release position of the draft rigging, said projecting abutment means being of such a size as to freely telescope within the hood of the yoke, said abutment means maintaining the butt end of the coupler shank spaced from the stop shoulder engaging portions of the follower, said follower having a flat rear face adapted to engage said shell to limit relative movement of the follower and shock

absorbing means; and a projection on the rear side of said follower adapted to cooperate with the shock absorbing means to compress the same, said last named projection being of greater width than the opening of the hood of the yoke and of such an overall size as to freely enter the open end of the shell. 80
